His Attorney.

UNITED STATES PATENT OFFICE.

CHARLES L. PERRY, OF SCHENECTADY, NEW YORK, ASSIGNOR TO GENERAL ELECTRIC COMPANY, A CORPORATION OF NEW YORK.

CONTROLLER.

1,247,446.

Specification of Letters Patent. Patented Nov. 20, 1917.

Application filed September 21, 1916. Serial No. 121,487.

To all whom it may concern:

Be it known that I, CHARLES L. PERRY, a citizen of the United States, residing at Schenectady, in the county of Schenectady, State of New York, have invented certain new and useful Improvements in Controllers, of which the following is a specification.

My invention relates to devices for controlling electric circuits, and has for its object the provision of improved means whereby the master switch which is ordinarily provided for controlling these circuits may be made considerably smaller, lighter and less expensive than those heretofore used.

My invention relates more specifically to devices having a plurality of contacts which successively control a circuit or circuits, such as for instance, as a controller which is commonly used for controlling an electric motor. Such controllers, ordinarily called "drum" controllers, employ a rotatable cylinder having a plurality of contact segments which engage corresponding stationary contact fingers to which the circuits to be controlled are connected. In the operation of controllers of this character, especially where the circuit to be broken is of a highly inductive character, dangerous arcing may occur at the circuit interrupting contacts. This is true, for instance, in the case of a master switch or controller which controls separate electromagnetically actuated switches. This arcing has necessitated the use of a comparatively large controller in which the spacing between the successive steps of the controller and the spacing between the various circuit interrupting contacts are sufficiently large to take care of the danger of the arc at one of the circuit interrupting contacts being deflected over to the adjacent contacts and thus causing a short circuit within the controller itself, and also to make sure that the controlled circuits will be positively deenergized. Of course, controllers have been constructed with large spacing between the successive operative positions and between the circuit making contacts, and have been provided with blow-out coils, arc deflecting plates of insulating material between the contact segments, and the like, in an attempt to obviate the difficulties and dangers above pointed out, but these have all involved complications which have been expensive to construct and maintain and have also added considerably to the weight and size of the controller.

One of the objects of my invention is to make possible the use of a small, light and inexpensive controller in which the spacing between the successive operative positions of the controller and the spacing between the various contacts are materially less than has heretofore been considered necessary. I do this by quickly deenergizing the controlled circuits and practically eliminating the dangerous arcing at the circuit interrupting contacts. I accomplish this object by connecting a circuit having a capacity successively in series with the inductive circuits to check the flow of current, at the same time connecting the circuit containing capacity across the circuit interrupting gaps to suppress the arcing. More specifically my invention comprises a controller for electric circuits having a plurality of segments which coöperate with corresponding contacts; some of the segments having two successively engaged sections insulated from each other, and a single condenser arranged to be successively connected across the gaps of the circuit interrupting contacts, that is, across the insulation between the sections of the segments, and in series with the coils of the electromagnetically actuated motor controlling switches to quickly check the flow of current in these coils and suppress any arcs which may tend to be formed as the controller is moved from step to step to deenergize these coil circuits.

One embodiment of my invention is shown in the accompanying drawing. Referring to the drawing, the motor 1 is connected to the supply circuit 2 by means of a trolley 3 and is connected to ground by means of the electromagnetically actuated switch member 4. The electromagnetically actuated switch member 5 is adapted to short circuit the armature controlling resistance 6 and electromagnetically actuated switch member 7 is adapted to short circuit the armature controlling resistances 6 and 8. The highly inductive actuating coils of these switches are controlled by means of a master controller 9 having two sets of relatively movable coöperating contacts. The size of these contacts, their spacing from one another and the spacing

between successive operative positions of the controller are all comparatively quite small. A condenser 10 having one side connected to the trolley pole 8 is adapted to check the flow of current in the switch coils and suppress any arcs which may tend to be formed at the master controller segments as the master controller is moved to deenergize the electromagnets. The movable contacts 10 of the master controller 9 comprise a plurality of contact segments, three of which are divided into two sections insulated from each other, the two sections being successively engaged by the stationary contacts 15 or finger. The sectional segments 11, 12, and 13, are electrically connected together and are adapted to successively complete the circuits for the coils of the electromagnetically actuated switches 4, 5 and 7, at their 20 respective contacts. The sectional segments 14, 15 and 16 are electrically connected together and are associated with but insulated from the sectional segments 11, 12 and 13, respectively. The condenser 10 is adapted 25 to be connected successively across the insulation between these sectional segments and in series with the coil circuits as the controller is moved to deenergize the magnets of the electromagnetically actuated switches 4, 30 5 and 7.

The operation of my device is as follows:—

In order to complete the circuit of the motor 1 through the resistances 6 and 8 to 35 the ground, the master controller 9 is moved through the positions *a* and *b* to the position *c*, when the coil 17 is energized causing the switch member 4 to close and complete the motor circuit. The circuit for the coil 40 17 is from the supply circuit 2, conductor 18, segment 19, and sectional segment 13, through the coil to ground. Moving the controller to the position *d* energizes the coil 20 and by moving the controller to the position 45 *e* the coil 21 is energized, causing the switch members 5 and 7, respectively, to close and short circuit the resistances 6 and 8 in the motor circuit.

To lower the speed of the motor, the controller is first moved backward to the position *d* when the sectional segment 11 is disconnected from the contact 22 and sectional segment 14 engages the contact 22. The condenser 10 is now connected in series with 50 the coil 21 through the sectional segment 14 so as to bridge the insulation between the sectional segments 11 and 14. The circuit for the coil 21 is now from the supply circuit 2, condenser 10, segment 23, sectional segment 14, contact 22 and coil 21 to ground. The condenser by checking the flow of current through the coil 21, promptly deenergizes the coil and causes the switch member 7 to open very quickly and remove the 55 60 65 short circuit from the resistance 8 in the

motor circuit. At the same time, due to the fact that the condenser is connected across the interrupting gap between sectional segment 11 and contact 22, any arc is promptly suppressed which may tend to be established 70 between sectional segment 11 and sectional segment 14 which is electrically connected with contact 22. Moving the controller to the position *c* disconnects the coil 21 from the condenser and connects the condenser in 75 series with the coil 20 through the contact 24 and across the insulation between the sectional segments 12 and 15, checking the flow of current in the coil 20, suppressing any arc which may tend to be formed between 80 the sectional segments 12 and 15, or between the sectional segment 12 and the contact 24, and causing the switch member 5 to open and remove the short circuit from the resistance 6. Moving the controller to the "off" 85 position through the positions *b* and *a* disconnects the coil 20 from the condenser and checks the flow of current in coil 17 thereby causing the switch member 4 to open the motor circuit, suppressing the arc at sectional segments 13 and 16 or sectional segment 13 and contact 25 and finally disconnecting the condenser from the coil 17. It will be seen that with my arrangement a 90 single condenser is connected across the interrupting gap and in the circuit of each actuating coil in succession so that the spark which would otherwise persist is eliminated by dissipation of the magnetic energy of these coils and the switches which they operate caused to open quickly. 95

By reason of the action of this single condenser in promptly suppressing the arcs at the circuit interrupting contacts and eliminating the danger of an arc flashing over 100 from any one of the contact segments to the adjacent segments, it has been possible to use a master switch in which the spacing between the successive operative positions *a*, *b*, *c*, *d*, *e*, and the spacing between the 105 segments themselves, as well as the sizes of many parts of the controller, are comparatively quite small in proportion to the 110 circuits controlled. This master switch or controller, may therefore be made considerably 115 smaller, lighter, and less expensive to manufacture and maintain and its life in service considerably lengthened.

In accordance with the provisions of the 120 patent statutes I have described the principle of operation of my invention, together with the apparatus which I now consider to represent the best embodiment thereof; but I desire to have it understood that the apparatus shown is only illustrative and that the 125 invention can be carried out by other means.

What I claim as new and desire to secure by Letters Patent of the United States, is:—

1. A controller for a plurality of electric circuits comprising a plurality of circuit in- 130

5 interrupting contacts for successively interrupting said circuits, and a single circuit having capacity arranged to be connected successively across each of the interrupting gaps as formed by the successive operation of said contacts.

2. A controller for a plurality of electric circuits comprising a plurality of circuit interrupting contacts for successively interrupting said circuits, and a condenser arranged to be connected successively across each of the interrupting gaps as formed by the successive operation of said contacts.

3. The combination with a controller having a plurality of contact segments adapted to make and break a plurality of circuits successively, of means comprising a single circuit having capacity for successively suppressing the arcs at the controller segments as they break their respective circuits.

4. A controller for a plurality of electric circuits comprising a plurality of circuit interrupting contacts for successively interrupting said circuits, a condenser and means for successively connecting the condenser in each of said circuits to check the flow of current as said contacts are opened.

5. A controller for a plurality of electric circuits comprising a plurality of circuit interrupting contacts for successively interrupting said circuits, a condenser and means for successively connecting the condenser in each of said electric circuits and across the corresponding interrupting gaps as formed by the successive operation of said contacts.

6. A controller for electric circuits comprising two sets of relatively movable co-operating contacts, one of which has two successively engaged sections insulated from each other, and a condenser arranged to be successively connected across the insulation between the sectional contacts.

7. A controller for electric circuits comprising two sets of relatively movable co-operating contacts, one of which has a plurality of successively engaged sections insulated from each other, a condenser, and means for successively connecting the condenser across the insulation between the sec-

tional contacts as the controller is moved to deenergize the circuits.

8. Controlling means for electric circuits comprising a plurality of electromagnetically operated switches, a controller having a plurality of successively engaged sectional contacts insulated from each other for controlling the electromagnets of said switches, a condenser, and means for connecting the condenser across the insulation between the sectional contacts as each successive electro- 55 magnet is deenergized.

9. A controller for electric circuits comprising two sets of relatively movable co-operating contacts, one of which has a plurality of successively engaged sections insulated from each other, a condenser, and means for successively connecting the condenser across the insulation between the sectional contacts and in series with the circuits as the controller is moved to deener- 60 65 gize the circuits.

10. Controlling means for an electric motor comprising a plurality of electromagnetically actuated switches, a controller having a plurality of successively engaged 75 sectional contacts insulated from each other for controlling the switch magnets, a condenser, and means for successively connecting the condenser to check the flow of current in the switch magnets and across the insulation between the sectional contacts to suppress the arcing as the controller is moved to deenergize the switch magnets.

11. Controlling means for a plurality of electric circuits comprising a controller 85 having a plurality of closely spaced, successively functioning, relatively movable, co-operating contacts, a condenser for increasing the safe capacity of the controller, and means for successively including the condenser in the controlled circuits and across the corresponding interrupting gaps as said circuits are successively broken at the contacts.

In witness whereof, I have hereunto set 95 my hand this 20th day of September, 1916.

CHARLES L. PERRY.
